UNITED STATES PATENT OFFICE.

JAMES D. CLEEK, OF ABINGDON, VIRGINIA.

VEHICLE-SPRING.

SPECIFICATION forming part of Letters Patent No. 416,053, dated November 26, 1889.

Application filed August 17, 1889. Serial No. 321,054. (No model.)

To all whom it may concern:

Be it known that I, JAMES D. CLEEK, a citizen of the United States, and a resident of Abingdon, in the county of Washington and State of Virginia, have invented certain new and useful Improvements in Vehicle-Springs; and I do declare the following to be a full, clear, and exact description of the invention, such as will enable others skilled in the art 5 to which it appertains to make and use the same, reference being had to the accompanying drawings, and to letters of reference marked thereon, which form a part of this specification.

15 Figure 1 of the drawings is a representation of this invention, and is a top view. Fig. 2 is partly a side view and partly a section.

The object of the invention is to provide a compound elliptic spring, in which the spring- 20 plates will be well bound together while preserving their freedom of motion; and the invention consists in the novel construction and combination of parts, as hereinafter set forth, and pointed out in the appended claim.

25 In the accompanying drawings, the letter A designates the main spring-plate, the ends of which are provided with eyes B in the usual manner.

C indicates the spring-plate which is next 30 to the spring-plate A, and shorter than the latter, its ends being gradually beveled, as at D, to correspond with the angular position of the capping-plates E, which overlie said ends, as shown.

35 F indicates a shorter spring-plate, which is placed upon the spring-plate C and is formed with the gradually-beveled ends G, which extend under the capping-plates.

Each capping-plate consists of a metallic 40 plate E, of sufficient length to extend from the eye of the main spring-plate over the beveled ends of the shorter spring-plates and being of equal breadth to said spring-plates. The capping-plate is provided with

45 small lugs H at the sides of its end portion, said lugs being bent downward at right angles to the plane of the plate and serving to engage the lateral edges of the main spring-plate to hold the capping-plate true.

50 The length of the lugs H is about equal to

the thickness of the main spring-plate. The upper or inner portion of each capping-plate is also provided with side lugs K, which are also bent downward at right angles to the plane of the capping-plate and are longer 55 than the lugs H, being long enough to project below the main spring-plate. The projecting ends of the lugs K are perforated, as indicated at L, to receive the ends of the transverse bearing-rod m, which may be provided with an anti-friction roller; or the projecting ends of said lugs K may be bent to extend toward each other under the main spring-plate to form the under bearing of the capping-plate. The upper or inner end portion of the capping-plate, which overlies the beveled end of the shortest spring-plate, is 60 preferably narrowed gradually to an angular point, as shown, to lessen the frictional bearing on the short spring and to give said bearing an elastic or yielding character, as it is designed that the capping-plate, while holding the ends of the spring-plates together in compact form shall not interfere with their freedom of movement.

Having described this invention, what I claim, and desire to secure by Letters Patent, is—

The compound vehicle-spring consisting of the main spring-plate, having its ends provided with eyes to receive fastening or connecting bolts, the gradually-shortened spring-plates overlying the main spring-plate and having beveled ends, and the capping-plates covering said beveled ends of the shorter 80 plates and having inward narrowed or tapered ends or points overlying the beveled ends of the uppermost spring-plate, said capping-plates having side pendent lugs, the outer lugs extending downward at the side edges 85 of the main spring-plate slightly inward from the end eyes of the latter plate, the inner lugs being connected together below the main spring-plate, substantially as set forth.

In testimony whereof I affix my signature 90 in presence of two witnesses.

JAMES D. CLEEK.
